Henry D. Fister

UNITED STATES PATENT OFFICE.

HENRY P. FEISTER, OF PHILADELPHIA, PENNSYLVANIA.

PRINTING-MACHINE.

SPECIFICATION forming part of Letters Patent No. 323,925, dated August 11, 1885.

Application filed October 31, 1883. (No model.)

To all whom it may concern:

Be it known that I, HENRY P. FEISTER, of the city of Philadelphia, county of Philadelphia, and State of Pennsylvania, have invented 5 an Improvement in Printing-Machines, of which the following is a specification.

My invention has reference to printing-machines; and it consists in certain improvements upon Letters Patent granted to me November 7, 1882, and numbered 267,172. In 10 that patent the sheet which is carried by one impression-cylinder, after being printed upon one side, is transferred to another impression-cylinder, being reversed by the operation, and 15 is printed upon the other, the transferring of the sheet from one cylinder to the other being effected by means of currents of air and nippers upon said cylinders. In this improvement I dispense with the use of air, and employ 20 in lieu thereof a transfer-frame secured to one of said cylinders and operating to throw the lower edge of the sheet over against the second impression-cylinder at the proper moment, which sheet is then caught by the nippers on said second cylinder and carried 25 around to receive the second impression, as fully set forth in the following specification, and shown in the accompanying drawings, which form part thereof.

30 In the drawings, Figure 1 is a side elevation of a printing-machine embodying my invention. Fig. 2 is an enlarged sectional elevation of a portion of the two impression-cylinders in the act of transferring the sheet from 35 one to the other. Fig. 3 is a front elevation of a part of the impression-cylinder provided with the transfer-frame, and Fig. 4 is a sectional view of the end of one of the adjusting-screws for the cams which actuate the nippers 40 and transfer-frames.

A is the frame of the machine, and may be provided with a track or guideway, A', upon which the endless bed of carriages B runs, which carriages support the type-forms.

45 C and D are the two impression-cylinders, and have impression-faces c and d, which are adapted to print from every alternate type-carriage, those which are omitted by cylinder D being printed from by cylinder C. There 50 may be any desired number of impression-surfaces upon these impression-cylinders. Each impression-surface is provided at the advance

end with nippers H, which are secured to a shaft, h, provided with a pinion, H', which meshes with a segmental gear, K', secured to 55 a shaft, k, to the end of which is secured a crank, K, which may be normally kept in one direction by a spring, k'. These nippers H are operated through the above mechanism by cams N, L, R, and R', which are pivoted 60 to the axis of the cylinders C and D, and may be adjusted by screws S, which pass through nuts T, pivoted to the frame A, the ends of said screws S being grooved, as at s, and received in the ends of socket-pieces S', which 65 are pivoted to the cams, being retained within said socket-piece by a screw or pin, s', and allowed to rotate freely therein.

Any other form of adjusting mechanism may be used in lieu of that just described. 70

E is the roll of paper, F F are the measuring rolls or cylinders, and G is the knife, which parts may be made substantially as shown in said patent of mine hereinbefore referred to, and also Letters Patent granted to 75 me April 18, 1882, and numbered 256,662. These impression-cylinders C and D and carriages B may be synchronously driven by means of gearing shown in said patents.

U are the inking-rollers, and are preferably 80 located between said impression-cylinders, and U' is a screen or shed to prevent the paper held by the impression-cylinders accidentally coming in contact with the said inking-rolls.

P are the transfer-frames, and consist of arms P', slotted at their bottoms, as at p', and are secured at their tops to rock-shafts p, carrying on their ends cranks O, which are drawn in one direction by springs o. Working on 90 the bottoms of said arms P' are the cross-bars P², which are secured thereto by screws P³. The bottoms of these plates or bars P² are notched, as at p², to allow the nippers to pass when clamping the bottom of the paper in the 95 act of transferring. The arm P' may be set in a recess, D², in the periphery of the cylinder D, and in the center thereof, so as to rest between the two impression-surfaces, which correspond to two pages, it being preferable to 100 print two-page sheets from each carriage B. If single-page sheets are to be printed, then there will be two arms, P'. In any case the arms P' and bars P² are arranged to come

upon the margins of the sheet, so as not in any manner to interfere with a perfect impression.

M is a shield to prevent the sheets falling away from the cylinder D. B' are the delivery-tapes. b is the fly-frame. b' is the receiving-table, and B' the folding and trimming mechanism, all these devices being clearly shown in Patent No. 256,662, hereinbefore referred to.

- 10 10 The operation is as follows: The paper E is fed between rollers or cylinders F and cut off by cutter G into sheets of the required size. The nippers H on cylinder D are held open by cam L, and as the crank K runs over the end thereof the said nippers close suddenly upon the end of the sheet and carry it forward. After being printed upon by the type-forms on carriages B it ascends, and the cam Q, acting on crank O, swings out the transfer-frame 15 15 P, thus throwing the bottom edge of the sheet X over within reach of the nippers H on the cylinder C, which have been kept open by cam R, and which suddenly close upon the said paper. At the same instant the cam N opens 20 20 the nippers H on the cylinder D, so as to allow the sheet to be carried off by cylinder C, and having been reversed it is printed upon the other side by the type-forms on one of the carriages B omitted by the cylinder D. The 25 25 cam R' then opens the nippers H, and the sheet, printed upon both sides, is carried off to the folding apparatus.

The cams L, N, Q, R, and R' may be accurately adjusted by the screw S, so as to actuate the nippers and transfer-frames at exactly the proper instant to insure the proper manipulation of the sheets.

While I prefer the construction shown, I do not limit myself to the details thereof, as they 35 35 may be modified in various ways without departing from my invention.

Having now described my invention, what I claim as new, and desire to secure by Letters Patent, is—

- 40 40 1. In a printing-machine, two impression-cylinders provided each with one or more impression-surfaces, in combination with a series of type-forms arranged to be passed in succession in contact with said cylinders, one 45 45 of which cylinders prints from alternate type-forms, and the other of which prints from those omitted, nippers arranged upon said cylinders, mechanism, substantially as described, to operate said nippers to catch and deliver the sheets, transfer-frames, substantially as described, pivoted to one of said cylinders and adapted to swing the tail end of the sheet over to the other cylinder, where it is caught by the nippers before the sheet has left the first 50 50 impression-cylinder, and mechanism, substantially as described, to operate said transfer-frames at the proper instant, substantially as and for the purpose specified.

- 55 55 2. In a printing-machine, two impression-cylinders provided each with one or more impression-surfaces, in combination with a series of type-forms arranged to be passed in

succession in contact with said cylinders, one of which cylinders prints from alternate type-forms, and the other of which prints from those omitted, nippers arranged upon said cylinders, mechanism, substantially as described, to operate said nippers to catch and deliver the sheets, transfer-frames, substantially as described, pivoted to one of said cylinders and adapted to swing the tail end of the sheet over to the other cylinder, where it is caught by the nippers before the sheet has left the first impression-cylinder, mechanism, substantially as described, to operate said transfer-frames at the proper instant, and devices, substantially as described, to adjust the time of operation of the transfer-frame mechanism, substantially as and for the purpose specified.

3. In a printing-machine, two impression-cylinders provided each with one or more impression-surfaces, in combination with a series of type-forms arranged to be passed in succession in contact with said cylinders, one of which cylinders prints from alternate type-forms, and the other of which prints from those omitted, nippers arranged upon said cylinders, cams to operate said nippers to catch and deliver the sheets, transfer-frames, substantially as described, pivoted to one of said cylinders and adapted to swing the tail end of the sheet over to the other cylinder, where it is caught by the nippers before the sheet has left the first impression-cylinder, mechanism, substantially as described, to operate said transfer-frames at the proper instant, and adjusting devices, substantially as described, to regulate the time of operation of nipper-cams, substantially as and for the purpose specified.

4. In a printing-machine, two impression-cylinders provided each with one or more impression-surfaces, in combination with a series of type-forms arranged to be passed in succession in contact with said cylinders, one of which cylinders prints from alternate type-forms, and the other of which prints from those omitted, nippers arranged upon said cylinders, cams to operate said nippers to catch and deliver the sheets, transfer-frames, substantially as described, pivoted to one of said cylinders and adapted to swing the tail end of the sheet over to the other cylinder, where it is caught by the nippers before the sheet has left the first impression-cylinder, cams to operate said transfer-frames at the proper instant, and adjusting devices, substantially as described, to regulate the time of operation of the said transfer-frame and nipper-cams, substantially as and for the purpose specified.

5. The combination of impression-cylinder D, nippers H, pivoted cam L to operate said nippers, screw S, nut T, and frame A, substantially as and for the purpose specified.

6. The combination of two impression-cylinders, each provided with one or more impression-surfaces, two or more type-forms arranged to be passed in contact with said impression-surfaces, which impression-surfaces on one cylinder print from certain type-forms,

and those of the other cylinder print from the type-forms omitted by the first, the impression-surface on said cylinders being adapted to pass close to each other and in opposite directions, 5 and mechanism, substantially as described, consisting of a transfer-frame carried by one cylinder, and nippers upon each cylinder, the said parts being so arranged that the transfer-frame moves one end of the sheet within reach of 10 the nippers upon the second cylinder, and by which it is caught at or about the time it is freed by the nippers upon the other or first cylinder, to automatically transfer the sheet printed on one side directly from one cylinder to 15 the other, and without being received and supported by intermediate stationary devices, substantially as and for the purpose specified.

7. The combination of impression-cylinders C and D, provided with nippers H, cranks K, 20 pivoted cams Q, L, N, R, and R', transfer-frames P, cranks O, adjusting-screws S, nuts T, frame A, and type-form-carrying devices, substantially as described, substantially as and for the purpose specified.

8. The combination of cylinder D, having a 25 grooved periphery, as at D², a transfer-frame, P, consisting of arm P' and adjustable cross-bar P², rod p, crank O, and cam Q, substantially as and for the purpose specified.

9. The combination of cylinder D, having a 30 grooved periphery, as at D², a transfer-frame, P, consisting of arm P' and adjustable cross-bar P², having notches p², rod p, crank O, and cam Q, substantially as and for the purpose specified.

10. The combination of an impression-cylinder and its nippers, cranks K, cams to operate said cranks pivoted to the axis of the cylinder, socket-piece S', adjusting screw-rod S, pivoted nut T, and frame A, substantially 40 as and for the purpose specified.

In testimony of which invention I hereunto set my hand.

HENRY P. FEISTER.
